His attys.

UNITED STATES PATENT OFFICE.

JACOB H. RIZOR, OF VAN WERT, OHIO.

ATTACHMENT FOR PLOWS.

1,296,319.

Specification of Letters Patent.

Patented Mar. 4, 1919.

Application filed June 11, 1918. Serial No. 239,366.

To all whom it may concern:

Be it known that I, JACOB H. RIZOR, a citizen of the United States, and a resident of Van Wert, in the county of Van Wert and the State of Ohio, have invented a certain new and useful Attachment for Plows; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to plows and particularly to a jointer and a fin attachment therefor. The object of my invention is the provision of an improved attachment of this class which is simple and inexpensive in its construction, efficient in its operation and capable of being easily and quickly attached to a plow.

Further objects and advantages of the invention will be apparent from the following detailed description thereof.

While the invention, in its broader aspect, is capable of embodiment in numerous forms, a preferred embodiment thereof is illustrated in the accompanying drawings, in which,—

Figure 1 is a rear perspective view of a plow embodying the invention. Fig. 2 is a fragmentary front perspective view thereof, and Fig. 3 is a horizontal section of the attachment.

Referring to the drawings, 1 designates a plow bottom of the customary or any suitable form, and 2 the beam carrying the same.

The attachment embodying the invention comprises a fin cutter 3, which, in the present instance, is of L-form with its lower arm extending rearward along the land side of the plow 1 and secured thereto by bolts 4 or in any other suitable manner. The upright portion of the fin 3 forms the cutting blade and extends at its upper end preferably to a height which is equal to, or greater than the height of the plow bottom. A frog 5 which has two diverging flanges is secured to the inner side of the cutter fin 3 adjacent to its upper end by bolts 6 extending through registering apertures in said fin and the abutting flange of the frog. A jointer blade 7 is secured by bolts 8 in the present instance, to the front side of the other flange

of the frog 5 and has its nose or forward edge portion preferably entering a curve or recess in the adjacent side of the fin 3 a short distance at the rear of its cutting edge so as to prevent the accumulation of weeds or other matter between the fin cutter and jointer. The jointer blade 7 is similar in form to the mold board of a plow and is preferably adjustably connected to the frog 1. Such adjustment in the present instance, is accomplished by the provision in the frog 5 of slots 9 through which the bolts 8 project.

A bracket arm 10, in the present instance of L-form, is adjustably clamped at one end to the plow beam 2 by the clamp 11 and extends forward therefrom with its free arm projecting downward between the flanges of the frog 5 and secured to the cutter fin engaging flange thereof by the bolt 6. A divider rod 12 extends upward and forward from the inner side of the jointer blade 7 and serves to gather trash, weeds and other matter and prevent the accumulation thereof around the base portion of the plow beam 2. The provision of this rod is found to be quite an important feature in the use of my attachment.

I wish it understood that my invention is not limited to any specific construction, arrangement or form of the parts, as it is capable of numerous modifications and changes without departing from the spirit of the claims.

Having thus described my invention, what I claim as new, and desire to secure by Letters Patent, is:—

1. The combination with a plow bottom and the beam therefor, of a bracket arm projecting forward and downward from the lower rear portion of said beam, a frog carried by said bracket, a cutter fin secured to said frog and extending downward and rearward therefrom at the land side of the plow bottom, and a jointer blade carried by said frog over the mold board side of the plow bottom.

2. The combination with a plow bottom and the carrying beam therefor, of a bracket arm adjustably extending forward from a lower rear portion of said beam, a frog carried by said bracket in advance of the plow bottom, a cutter fin extending downward from said frog in advance of the plow bottom and secured at its lower portion to the outer side of the land side of the plow bot-

tom, and a jointer blade adjustably carried by said frog and extending from the adjacent side of the fin cutter over the forward portion of the mold board side of the plow bottom.

3. The combination with a plow bottom and the carrying beam therefor, of a bracket arm extending forward from the lower rear portion of said beam, a frog carried by said bracket arm in advance of the plow bottom, a fin cutter secured to and extending down-

ward from said frog in advance of the land side of the plow, and secured at its lower end portion to the plow bottom at said side, a jointer blade carried by said frog over the forward end portion of the mold board of the plow and having its forward edge in close engagement with the adjacent side of the fin cutter.

In testimony whereof I have hereunto signed my name to this specification.

JACOB H. RIZOR.
